DOOR LOCK

George Chieger, Birmingham, and Harold J. Borneman, Detroit, Mich., assignors to Fruehauf Corporation, a corporation of Michigan

Filed June 18, 1963, Ser. No. 288,785
3 Claims. (Cl. 292—241)

This invention relates generally to door locks and more particularly to an improved shrouded "anti-rack" door lock for van-type highway vehicles and the like.

The forces to which the doors and door frames of van-type vehicles are subjected are known in the art as "racking" forces. These forces tend to move the doors vertically relative to one another and to the door frame. Because the doors and door frames of such van-type vehicles are generally utilized to insure the structural integrity of the van, the locks for the doors of such vehicles must be of relatively strong construction in order to withstand the "racking" forces and positively retain the doors properly closed within their door frames.

Door locks characteristically transfer "racking" forces from the door panels to the door frame through the closing and locking elements of the lock and thence through the connecting bars extending between vertically aligned locks. However, subjection of the locking elements and connecting bars of the door lock to such racking forces results in premature wear and flexure thereof, ultimately reducing the effectiveness of the locking elements and connecting bars in closing and locking the door and thus, the ability of the door to impart structural rigidity to the van of the vehicle. Further, tolerance and operating clearance requirements inherently necessary in the locking elements and connecting bars in order to implement operation thereof, tend to reduce the ability of the lock to transfer "racking" forces to the door frame.

The foregoing problems are solved in part by a door lock in accordance with application Serial No. 185,429 filed April 5, 1962 and assigned to the assignee of the instant invention. A door lock in accordance with the aforesaid application imparts the inherent lateral rigidity of the door panels to the door frame by transferring "racking" forces through an "anti-rack" element. The "racking" forces between the door and door frame are absorbed by the "anti-rack" elements of the door lock, thereby relieving the locking tongues and connecting bars from the "racking" forces. In other words, the locking function of the lock is segregated from the "anti-rack" function.

However, it has been found that the high humping loads due to, for example, railroad piggyback operation, places considerable outward loads on trailer doors and their hardware. These high loads tend to bend the lock connecting bars or shafts.

In addition, the offset force applied to the lock cam finger creates a moment tending to twist the lock connecting bars in an opening direction. If, as disclosed in the aforesaid application the bars are locally flattened to accommodate the complementary flats of the lock handle, this flattened portion of the bars becomes twisted with heavy torque loads so that the door cannot be cammed tight.

Further, such locks are relatively susceptible to icing and damage by collision.

An improved door lock in accordance with the instant invention comprises a lock frame that is rigidly mounted on the door panel. The frame has a central bore therein for journaling of the connecting bar or shaft at two axially spaced points. A locking element or tongue extends radially outwardly from the connecting bar for engagement with a box-like element on a keeper fixture. Cooperation between the locking tongue and keeper ele-

2

ments cam the door to the closed condition and retain the door in said closed condition.

Further, an improved cam finger configuration materially reduces any twisting or opening moment on the connecting bar.

An "anti-rack" shroud is formed integrally with the lock frame for engagement over a complementary outer surface of the keeper fixture. Racking forces between the door and door frame are absorbed by the "anti-rack" shroud, thereby relieving the locking elements and connecting bars from "racking" loads. The shroud also protects the locking tongue against ice accumulation, impact, damage, etc.

Accordingly, one object of the instant invention is an improved door lock.

Another object of the instant invention is a door lock that segregates closing forces operative thereon from the "racking" forces to which the lock is subjected.

Another object is a door lock wherein "racking" forces between the door and frame are absorbed by a rigid "anti-rack" shroud on the door that is engageable over a complementary element on a keeper fixture on the door frame.

Another object of the instant invention is a door lock that supports the outboard ends of the connecting bar that extends between aligned door locks.

Other objects and advantages of the instant invention will be apparent in the following specification, claims and drawings, wherein:

FIGURE 1 is a rear view of a van-type vehicle having the improved door locks of the instant invention;

FIG. 2 is a fragmentary view taken within the circle "2" of FIG. 1;

FIG. 3 is a cross-sectional view taken substantially along the line 3—3 of FIG. 2;

FIG. 4 is a cross-sectional view taken substantially along the line 4—4 of FIG. 2;

FIG. 5 is a cross-sectional view taken substantially along the line 5—5 of FIG. 2;

FIG. 6 is a fragmentary view of the locking tongue; and,

FIG. 7 is a cross-sectional view taken along the line 7—7 of FIG. 6.

As best seen in FIGURE 1 of the drawings, a plurality of improved door locks 10, in accordance with an exemplary constructed embodiment of the instant invention are shown operatively associated with the rear door panels 12 and 14 and door frame 16 of a van-type vehicle 18. The doors 12 and 14, door frame 16, and van 18 are conventional in construction.

A pair of connecting bars 22 and 24 connect vertically aligned pairs of the locks 10 and have handles 26 and 28 thereon to facilitate rotation of the locking elements of the locks 10, as will be described.

The door locks 10 are of like construction except that they are of left and right hand orientation. Thus, for the purpose of clarity only one of the door locks 10 will be described hereinafter.

As best seen in FIG. 2 of the drawings, each lock 10 comprises a frame 30 made of, for example, cast steel, having vertically aligned bores 40 and 41 therein for the acceptance of a lower end 42 of the connecting bar 22 and lower end portion 43 of a tongue element 44, respectively. An upper end 45 of the tongue element 44 is secured within a central bore 46 in the connecting bar 22, as by welding.

The frame portion 30 of the lock 10 is secured to the door 12 as by a plurality of bolts 50 which extend through complementary apertures in the door 12. The frame portion 30 is positively located relative to the door 12 by a pair of enlarged bosses 52 and 54 which extend

through complementary apertures 56 and 58 on the door 12 to accept shear forces therebetween.

The locking tongue element 44 has a radially extending tongue portion 60 with outwardly convergent upper and lower surfaces 62 and 64, respectively, for acceptance under a tongue keeper element 66 on a keeper fixture 68. The keeper fixture 68 is secured to the frame 16, as by welding. The tongue keeper element 66 has tapered surfaces 70 and 72 complementary to the surfaces 62 and 64 on the tongue 60.

As best seen in FIG. 3, the tongue keeper element 66 on the fixture 68 has an arcuate face 74 to effect a camming action with a complementary curved surface 78 on the tongue portion 60 of the tongue element 44. As the door 12 is swung toward the closed position with respect to the frame 16, an outer end portion 82 of the tongue 60 engages behind the arcuate surface 74 on the tongue keeper element 66 of the keeper fixture 68. Subsequent rotation of the connecting bar 22 and locking tongue element 44 cams the door 12 to the closed condition with respect to the door frame 16. It is to be noted that the bearing point between the tongue 60 and tongue keeper element 66 is relatively closely spaced to the axis of rotation of the tongue element 44 to minimize any opening moment on the element 44 due to rearwardly shifting loads on the doors 12 and 14.

In accordance with one feature of the instant invention the lower end 43 of the tongue element 44 is journaled in the bore 41 in the frame 30. Thus, the tongue element 44 is supported at two axially spaced points to preclude bending or canting thereof.

In accordance with another feature of the instant invention, the lock frame 30 is provided with an integral rearwardly opening shroud 100 that is of box-like exterior configuration and generally V-shaped internal vertical cross-section defined by convergent surfaces 102 and 104.

As the door 12 and therefore the lock frame 30 and "anti-rack" shroud 100 rotate towards the closed position with respect to the door frame 16, the surfaces 102 and 104 on the "anti-rack" shroud 100 are engaged over a pair of complementary surfaces 106 and 108 on the keeper element 68, positioning the door 12 vertically with respect to the frame 16 and precluding subsequent relative vertical movement therebetween.

It should be apparent that, because the "anti-rack" shroud 100 on the frame 30 and "anti-rack" keeper element 68 on the door frame 16 absorb vertical shear forces between the door 12 and frame 16, the tongue element 44 and connecting bar 22 that extends between the vertically aligned locks 10 are not subjected to vertical loads upon the tendency of the door 12 to move vertically relative to the frame 16. In other words, the locking tongue element 44 is utilized solely for a closing and locking function, whereas the "anti-rack" shroud 100 and complementary keeper 68 provide the "anti-rack" function. Accordingly, the locking tongue element 44 and locking bar 22 can, in effect, float vertically relative to the frame 30 of the lock 10, thereby eliminating the deleterious wear and flexure.

From the foregoing description it should be apparent that the instant invention solves the problem of minimizing the effect of rearwardly directed loads on the door lock by providing the tongue portion of the tongue element with a generally arcuate surface that is so shaped as to bring the central rotative axis of the tongue element to close proximate relation to a longitudinal plane drawn through the bearing point of the tongue element on the tongue keeper element. Thus, rearwardly directed loads on the doors of the van have a relatively small moment on the tongue element thereby minimizing the tendency of such shifting loads to open the doors. In addition the shroud on the door lock substantially encloses the keeper

and tongue elements to minimize the effects of ice, snow etc. as well as serve an "anti-rack" function.

Yet another feature of the door lock of the instant invention is that the tongue element thereof is supported at two axially spaced points to preclude bending thereof.

It is to be understood that the specific construction of the improved door lock herein disclosed and described are presented for the purpose of explanation and illustration and are not intended to indicate limits of the invention, the scope of which is defined by the following claims.

What is claimed is:

1. An anti-rack door lock for a vehicle having a door pivotally supported within a complementary door frame, said lock comprising
  - a lock frame rigidly attached to the vehicle door having a box-like shroud overlying the door frame, the shroud on said frame having an aperture facing the door frame and an outwardly divergent truncated conical internal recess therein,
  - a keeper fixture rigidly attached to the door frame having a truncated conical portion complementary to the shroud on said lock frame and acceptable therein to absorb racking forces having a vector generally parallel to the axis of rotation of the door relative to the door frame and a tongue keeper element spaced from said door frame, and
  - a locking tongue element rotatably supported by said lock frame at two axially spaced points and movable between a locked condition and an unlocked condition, said locking tongue element having a tongue portion engageable with the tongue keeper element on said keeper fixture to retain the door in the locked condition.
2. An anti-rack door lock for a vehicle having a door pivotally supported within a complementary door frame, said lock comprising
  - a lock frame rigidly attached to the vehicle door having a box-like shroud overlying the door frame, the shroud on said frame having an aperture facing the door frame and an outwardly divergent truncated conical internal recess therein,
  - a keeper fixture rigidly attached to the door frame having a truncated conical portion complementary to the shroud on said lock frame and acceptable therein to absorb racking forces having a vector generally parallel to the axis of rotation of the door relative to the door frame and a tongue keeper element spaced from said door frame, and
  - a locking tongue element having a tongue portion rotatably supported by said lock frame on opposite sides of the tongue portion, the tongue portion of said locking tongue element having an arcuate portion engageable with a complementary arcuate portion on the tongue keeper element on said keeper fixture to retain the door in the locked condition, the shroud on said lock frame substantially enclosing said keeper fixture, and locking tongue element when the door is in the closed condition relative to said door frame.
3. A door lock in accordance with claim 2 wherein the arcuate portion of said locking tongue element extends relatively closely to the axis of rotation of said tongue element to minimize the opening moment of the tongue keeper element thereon when the door is in the closed condition.
